LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-OPERATED PERCUSSIVE TOOL.

1,126,943.

Specification of Letters Patent.

Patented Feb. 2, 1915.

Application filed June 9, 1914. Serial No. 843,926.

To all whom it may concern:

Be it known that I, LEWIS C. BAYLES, a citizen of the United States, residing at Easton, in the county of Northampton and State of Pennsylvania, have invented a certain new and useful Improvement in Fluid-Operated Percussive Tools, of which the following is a specification.

This invention relates to fluid operated percussive tools, and more particularly to tools of the type wherein the admission of fluid is controlled primarily by the movement of the piston.

The object of this invention is to provide an auxiliary valve for controlling the admission of fluid to one portion of the cylinder to increase the efficiency of the piston blow. This object is accomplished by the invention, a practical embodiment of which is shown in the accompanying drawings, in which,

Figures 1 and 2 are longitudinal sections showing the piston and auxiliary valve in different positions.

In the drawings is shown a cylinder 1 which consists of a smaller forward bore 2 and a larger rearward bore 3. In the cylinder 1 is a piston 4 having a head 5 sliding in the rearward bore 3 and a hammer bar 6 sliding in the forward bore 2, there being a neck 7 between the hammer bar and the head of the piston. Fluid is admitted constantly to the forward end of bore 2 by a passage 8. From the forward end of bore 2, somewhat rearward of the passage 8, a passage 9 leads to the rearward end of the bore 3. From the passage 8 a passage 10 leads rearwardly along the cylinder, this passage having two ports, 11 and 12, opening into the rearward end of bore 2, the forward of these, 11, being so placed as to be uncovered by the hammer bar 6 and allow fluid to pass to the forward end of the bore 3, when the piston is practically at the forward end of its stroke, while the rearward port 12 when open admits fluid for a considerable portion of the piston stroke. To control the port 12 a valve 13 is provided which has a head 14 sliding in a valve chest 15 and a port controlling portion 16 adapted to project into port 12 and close it from communication with passage 10. The inner end of the valve chest 15 is connected with the forward end of bore 3 by a passage 17, while the outer end is connected with the

rear end of bore 3 by a passage 18. An exhaust passage 19 is provided for both ends of the rear bore 3, it being so placed as to be uncovered by the piston near the end of the piston stroke in each direction.

In operation, supposing the parts to be in the positions shown in Fig. 1, air is being admitted to the forward end of bore 2 and to the rear end of bore 3 through the passage 9. Under such conditions there will be pressure in the outer end of valve chest 15 and no pressure in the inner end, the forward end of bore 3 being open to atmosphere through port 19. The pressure in the rear end of bore 3 on the larger area of the piston head, will drive the piston forwardly against the pressure on the forward end of the hammer bar 6, the fluid in the front of bore 3 exhausting for part of the stroke through port 19. As the piston moves forwardly the hammer bar 6 will cover the passage 9 so that the fluid in the rear end of the bore 3 will act expansively to move the piston forward. Further movement of the piston will cause the hammer bar 6 to uncover the port 11. This will admit air to the forward end of bore 3 and at the same time the exhaust port 19 will be uncovered by the rear face of the piston head exhausting the rear end of the cylinder and also the outer end of the valve chest 15 through the passage 18. The pressure in the inner end of the valve chest 15 through the passage 17 and also the pressure on the end of the port controlling portion 16 will move the valve 13 outwardly opening the port 12. This will allow fluid to enter the front end of the bore 3 for a considerably longer period during the back stroke than during the forward stroke and thus will produce a full backward stroke of the piston, while by reason of the fact that the port 12 is closed during the forward stroke, the piston will strike a much harder blow on account of the absence of a live air cushion in the front end of bore 3.

It is to be understood that while the present showing and description discloses only one specified modification of the invention, other forms and modifications are included in the spirit and scope of the invention as expressed in the claims.

What I claim is:

1. In a percussive tool, a cylinder, having a larger rearward portion and a smaller for-

ward portion, a piston in said cylinder having a head in said rearward cylinder portion and a hammer bar in said forward cylinder portion, means for admitting fluid constantly to the forward end of said cylinder, a passage controlled by the piston for admitting fluid to the rearward end of said larger cylinder portion, a passage for admitting fluid to the forward end of said larger cylinder portion, a valve controlling said passage, and means for moving said valve to open said passage near the forward end of the piston stroke.

2. In a percussive tool, a cylinder, a piston having two smaller surfaces for driving it in one direction and a larger surface for driving it in the other direction, means for admitting pressure constantly to one of said smaller surfaces, means for admitting fluid intermittently to the other of said smaller surfaces comprising a valve, and means for admitting fluid intermittently to said larger surface.

3. In a percussive tool, a cylinder, a piston having a head and a hammer bar, means for admitting fluid to exert a constant pressure on the forward end of said hammer bar, means controlled by said piston for admit-

ting fluid intermittently to exert pressure on the rear of said piston head, and means comprising a valve for admitting fluid intermittently to exert pressure on the forward face of said piston head.

4. In a percussive tool, a cylinder, a piston having a head and a hammer bar, means for exerting a constant fluid pressure on the forward end of the hammer bar, means for exerting an intermittent fluid pressure on the rearward face of said piston head, and means for exerting an intermittent pressure on the forward face of said piston head comprising a valve.

5. In a percussive tool, a cylinder, a piston having a head and a hammer bar, means for exerting a constant fluid pressure on the forward end of the hammer bar, means for exerting an intermittent fluid pressure on the rearward face of said piston head, and means for exerting an intermittent pressure on the forward face of said piston head.

In testimony whereof, I have hereunto set my hand.

LEWIS C. BAYLES.
